UNITED STATES PATENT OFFICE.

BERG HEINRICH, OF ANDERSON, INDIANA, ASSIGNOR TO MID-WEST BOX COMPANY,
OF ANDERSON, INDIANA, A CORPORATION OF INDIANA.

MACHINE FOR MAKING CORRUGATED BOARD.

Application filed August 18, 1919. Serial No. 318,088.

To all whom it may concern:

Be it known that I, BERG HEINRICH, a citizen of the United States, and a resident of Anderson, in the county of Madison and 5 State of Indiana, have invented certain new and useful Improvements in Machines for Making Corrugated Board, of which the following is a full, clear, and exact description.

10 The invention relates to machines for making corrugated board and more particularly to the mechanism employed for cutting the continuous web into sheets of the desired size.

15 The object of the invention is to provide an improved cutting mechanism adapted to sever the sheets from the web which is readily adjustable to adapt it to successively cut sheets of different lengths.

20 A further object of the invention is to provide improved cutting mechanism in which the cutters are mounted on a carriage which is adapted to move with the web and which is operative by a spring or yielding connection which causes the cutters to grip the web and keep it under a slight pressure during the cutting operation, for the purpose of preventing any buckle in the web. Another object of the invention is to provide 25 simple means for automatically stacking the severed sheets.

Other objects of the invention will be apparent from the specification.

The invention consists in the several novel 30 features hereinafter set forth and more particularly defined by claims at the conclusion hereof.

In the drawings: Figure 1 is a side elevation of a machine embodying the invention. 40 Fig. 1^a is a detail of the web-operated controlling device for the cutter driving mechanism. Fig. 1^b is a section taken on line 1^b—1^b of Fig. 1^a. Fig. 2 is a plan. Fig. 3 is a central vertical longitudinal section of the 45 cutter mechanism. Fig. 3^a is a detail perspective of the yielding connection in the cutting operating mechanism. Fig. 4 is a detail section of the clutch through which the cutting mechanism is operated. Fig. 5 is an end elevation. Figs. 6 and 7 are details of the connection for operating the cutter carriage and cutter, showing the parts in different positions. Fig. 8 is a section 50 taken on line 8—8 of Fig. 7, parts being 55 shown in elevation.

The machine comprises a frame 9 which may be of any suitable construction and in which are mounted in cooperative relation the rolls 10 which may be the final rolls acting on or for feeding the corrugated board. 60 These rolls are continuously driven synchronously with the machine for corrugating the web and applying the facing sheet or sheets thereto, so that the surface-speed of these rolls will correspond to the travel of the 65 finished web. These rolls are coaxially driven by gears 11, one of which will be driven by suitable mechanism from the driving mechanism of the machine for making the corrugated board or by other mechanism 70 driven in synchronism with the machine.

A gear-wheel 12, fixed to the shaft of the lower roll 10, meshes with a pinion 13 on a shaft 14 which is mounted in bearings 15 on the frame 9. A sprocket wheel 16 on the 75 shaft 14, a chain 17, driven by said sprocket, and a sprocket 18, fixed to a clutch-wheel 19, serve to drive said wheel continuously while the corrugated board machine is in operation. Wheel 19 constitutes the continuously 80 driven member of a clutch, the operation of which is controlled by the web, for intermittently operating the cutter mechanism. Wheel 19 is loose on a shaft 20 and serves to 85 drive said shaft through a pair of dogs 21 which are pivoted, as at 22, in a collar 23 fixed to said shaft. Springs 24, connected to said arms respectively and to posts 25 on said collar, serve to normally pull the arms into engagement with the internal friction- 90 face 26 of the wheel 19. An equalizing bar 27 is connected to the dogs by links 28. This bar causes the dogs to be conjointly shifted into or out of engagement with the clutch 95 wheel 19. A trip pin 29 is fixed to one of the dogs and is adapted to be caught by a notch 30 in a bar 31 which has its lower end pivoted to the frame, as at 32. In operation, when the pin 29 passes into the notch 30 and is arrested by stop-bar 31, both of the 100 dogs will, through the equalizer bar 27, be held against rotation and disengaged from the clutch wheel 19. When the stop bar 31 is withdrawn from the path of pin 29, springs 24 will draw the dogs into operative 105 engagement with the friction face 26 of the clutch wheel 19 and cause the shaft 20 to be driven. The stop-notch and trip-pin 29 are adapted to arrest the shaft at but one point, so that upon each operation of the stop-bar 110

the shaft 20 will make one complete revolution.

The invention contemplates controlling the clutch for operating the cutter mechanism, by the web of paper, and for this purpose, a controller-arm 33 is pivoted, as at 34, in a bracket 35 held on a bar 36 which is suitably secured to the frame. This arm is adapted to be engaged and shifted by 10 the front edge of the web and when the arm is rocked about its pivot 34, its lower end will engage a collar 37 which is fixed on a releasor-bar 38 that is slidably mounted in roller-guides 39 which are suitably sustained by the frame-work of the machine. The inner end of bar 38 is pivoted, as at 40, to the clutch-stop 31. As a result, when the front edge of the web engages and shifts the dog 33, the stop-bar 31 will be operated 15 to release pin 29 and render operative the clutch for driving the cutting mechanism. To adapt the controlling mechanism for different lengths of sheets, bracket 35, in which arm 33 is pivoted, is slidably adjustable on the bar 36 and is adapted to be conveniently secured in assigned position along said bar by cam-lever 42. This clutch and controlling mechanism exemplify a start and stop mechanism for the cutter-driving mechanism 20 which is controlled by the end of the web. Also one in which the controlling mechanism is adjustable so that it can be quickly set to sever sheets of different lengths from the continuously fed web by shifting the 25 arm 33 which is operated by the end of the web.

The cutter-mechanism comprises a carriage 44 which is slidably mounted on the frame 9 and comprises a bed 45, over which the web is fed by rollers 10. A cutter 46 is secured to the front end of the bed 45 and a rotary cutter 47 is secured to a mutilated roller 48 which is mounted to rotate in bearings 49 on the carriage 44. Normally, when the cutter-mechanism is at rest, the cutters are in the relative position shown in Fig. 3, so that the web will be free to pass between them until the rotary cutter is operated toward the cutter 46. A sprocket 50 on the clutch-shaft 20 drives a chain 51 which operates a sprocket 52 on a cross-shaft 53 which is mounted in fixed bearings 54. Crank-disks 55 are secured to the ends of shaft 53 respectively. This driving connection for the shaft 53 serves to operate this shaft a complete revolution every time that the clutch is rendered operative. Disks 55 serve to reciprocate the cutter-carriage 44 by means of links 56 which are pivoted, as at 57, to the crank-disks, and, as at 58, to bars 59, which are held on the sides of the carriage 44 by bolts 60, which pass through slots 61 in said bars and permit movement of the bars relatively to the carriage. The bars 59 operate the carriage

through yielding connections consisting of rods 62 which are fixed to the bars 59 respectively and pass and slide through guides 63 which are fixed to the carriage 44, and springs 64 which are engaged by members 65 on the rear end of rods 62, so that the power applied to the bars 59 will be yieldingly applied to the carriage during its forward movement. During retraction of the carriage, a shoulder 59' on each bar 59 will engage guide 63 and positively shift the carriage. The rotary cutter-roll 48 has affixed to one of its ends an arm 66 which is connected to one of the links 56 by a short vertical link 67. The vertical movement of this link 67 operates the cutter-roll 48 to which the rotary cutter 47 is secured during the advance of the cutter-carriage. A characteristic of this construction is that the yielding connection makes it possible to operate the carriage at a slightly differential with respect to, or greater speed than, the web, so that when the latter is gripped between the cutters, the yielding connections will permit the cutters to grip the corrugated board and keep it under a slight tension.

As soon as the sheet is cut from the web, during the advance of the carriage, the carriage will be free to be moved away from the end of the web by the force of the springs 64. This will cause the rotary cutter to keep clear of the end of the web until the latter has been rocked upwardly sufficiently to permit the web to pass under it.

An abutment 70 on member 65 of one of the yielding connections (Fig. 3a) is adapted to retract the stop-bar 31 and the releasor-bar 38 to restore the controller dog 33 to its normal position at the end of the outstroke of the cutter-carriage.

That portion of the web which projects beyond the cutter-roll is supported at one side by a rail 75, whilst its other side is unsupported. A rail 75 is supported on legs 76 and an inclined support 77, consisting of rails between legs 76 and base-boards 78, is disposed to catch the sheets after they have been severed from the web, the sheets falling by gravity onto said support and forming a stack. This appliance exemplifies means for automatically stacking the sheets as they are cut from the web.

In operation, the finished corrugated web will be fed continuously from the rolls 10 and when its front edge engages the controller-arm 33, the latter will operate the releasor-bar 38 to shift the stop-bar 31 and release the trip-pin 29 of the clutch. Thereupon, the clutch will become operative to drive shaft 53 and the crank-disks 55 on shaft 53 one revolution. These disks, through links 56, will operate bars 59 to reciprocate the carriage through the yielding connections and simultaneously the rotary cutter will be operated by means of arm 66.

and link 67 so that a sheet will be severed from the web during the initial portion of the forward stroke of the carriage. After the sheet has been cut, it will be without support, except at one side of the rail 75, so that its other side will fall by gravity and build up a stack on the inclined support 77. As the carriage approaches the end of its outstroke, abutment 70 will strike the stop-arm 31, so that the trip-pin 29 will be arrested by the notch 30 in said arm, when the clutch-shaft has made one complete revolution, so that the cutter-carriage will be arrested at the starting point and remain idle until the front edge of the web again contacts with the controller arm 33 to start the cutter-mechanism as before and repeat the cutting operation. Obviously, by adjusting the controller arm 33 and collar 37, which is adjustable on rod 38, so that the arm will be engaged by the edge of the web when different lengths thereof have been projected beyond the cutters, the length of the sheets may be varied as desired without varying the operation of any of the cutter-mechanism or any other change, except said adjustment.

The invention exemplifies improved intermittently operated cutter mechanism under control of a device which is operable by the edge of the web so that the lengths of the sheets may be varied as desired. Also mechanism in which the reciprocating cutter mechanism is operated by a yielding connection so that it is not necessary to operate the carriage and the web in strict synchronism, to avoid buckling of the web. Also cutter mechanism which is operable in conjunction with means for automatically stacking the severed sheets by gravity.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of mechanism for continuously feeding a web of flexible material, such as corrugated board, power operated cutter mechanism for severing sheets from the web, and means for controlling the operation of the cutter mechanism comprising an element which is sufficiently sensitive to be shifted by and which engages the edge of the flexible web without buckling and connected to start said mechanism, and power-operated means to automatically restore said element to a predetermined normal position after each operation.

2. In a machine of the character described, the combination of mechanism for continuously feeding a web of flexible material,

such as corrugated board, power-operated cutter mechanism for severing sheets from the web, and means for controlling the operation of the cutter mechanism comprising an element which is sufficiently sensitive to be shifted by and which engages the edge of the flexible web without buckling and connected to start said mechanism, and power-operated means to automatically restore said element to a predetermined normal position after each operation, said element being adapted to remain in the path of the edge of the web.

3. In a machine of the character described, the combination of mechanism for feeding a web of flexible material, such as corrugated board, cutter mechanism reciprocable with and in the direction of the web, mechanism stationarily mounted for reciprocating the cutter mechanism, and means for controlling the operation of the cutter mechanism comprising an element which is sufficiently sensitive to be shifted by and which engages the edge of the flexible web without buckling it and connected to start said mechanism.

4. In a machine of the character described, the combination of mechanism for continuously feeding a web of flexible material, such as corrugated board, power-operated cutter mechanism for severing sheets from the web, and means for controlling the operation of the cutter mechanism comprising an element which is sufficiently sensitive to be shifted by and which engages the edge of the flexible web without buckling and connected to start said mechanism, and means to automatically restore said element to a predetermined normal position after each operation, said feeding mechanism being entirely disposed to engage the web before it reaches the cutter mechanism and adapted to leave the sheets free when they have been severed from the web.

5. In a machine of the character described, the combination of mechanism for continuously feeding a web of flexible material, such as corrugated board, power operated cutter mechanism for severing sheets from the web, and means for controlling the operation of the cutter mechanism comprising a bar and an element which is sufficiently sensitive to be shifted by and which engages the edge of the flexible web without buckling it and connected to start said mechanism, means to automatically restore said element to a predetermined normal position after each operation, and clamping means whereby said element may be positioned at any point on said bar.

6. In a machine of the character described, the combination of mechanism for continuously feeding a web, reciprocable cutter-mechanism movable in the line of travel of the web, and mechanism for reciprocating the cutter mechanism, including a yield-

ing connection through which the cutter-mechanism will be shifted during its movement in the direction of the travel of the web, to permit the operating mechanism 5 to travel differentially with respect to the cutter-mechanism during the cutting of the web.

7. In a machine of the character described, the combination of mechanism for continuously feeding a web, reciprocable cutter-mechanism movable in the line of travel of the web, and mechanism for reciprocating the cutter mechanism, including a spring-connection through which the cutter 10 mechanism will be shifted during its movement in the direction of travel of the web to permit the operating mechanism to travel differentially with respect to the cutter mechanism during the cutting operation.

20. 8. In a machine of the character described, the combination of mechanism for continuously feeding a web, reciprocable cutter mechanism movable in the line of travel of the web, and mechanism for reciprocating the cutter mechanism, including a crank, a link and a yielding connection through which the cutter mechanism will be shifted, to permit the operating mechanism to travel differentially with respect to the cutter 25 mechanism during the cutting operation and its travel in the direction of the travel of the web.

9. In a machine of the character described, the combination of mechanism for continuously feeding a web, a reciprocable carriage movable in the line of travel of the web, a cutter movably mounted on the carriage, mechanism for advancing the carriage with the web, comprising a yielding connection through which the carriage will be 30 shifted during its movement in the direction of travel of the web, and means for operating the cutter on the carriage.

40. 10. In a machine of the character described, the combination of mechanism for continuously feeding a web, a reciprocable cutter carriage movable in the line of travel of the web, a cutter rotatably mounted on the carriage, mechanism for advancing the 45

carriage with the web, comprising a yielding connection through which the carriage will be shifted during its movement in the direction of travel of the web, and means for rotating the cutter on the carriage. 50

11. In a machine of the character described, the combination of mechanism for continuously feeding a web, a reciprocable carriage movable in the line of travel of the web, a cutter movably mounted on the carriage, mechanism for advancing the carriage with the web, comprising a connection through which the carriage will be yieldingly shifted during the cutting operation and its travel in the direction of the travel of the web and will be positively 55 shifted during retraction of the carriage, and means for operating the cutter on the carriage. 60

12. In a machine of the character described, the combination of mechanism for continuously feeding a web, reciprocably operated cutter mechanism for severing sheets from the web, means to support the web which has passed the cutter mechanism at one side only so its other side will be free 70 to fall after the web has been severed, means for controlling the operation of the cutter mechanism, comprising a controlling element at the supported side of the web, and means beneath the web onto which the severed sheets will fall by gravity and 75 form a stack. 80

13. In a machine of the character described, the combination of mechanism for continuously feeding a web, reciprocably operated cutter mechanism for severing sheets from the web, means to support the web which has passed the cutter mechanism at one side only so its other side will be free to fall after the web has been severed, means for controlling the operation of the cutter mechanism, comprising a controlling element at the supported side of the web, and an inclined support beneath the web onto which the severed sheets will fall by gravity and 85 form a stack. 90

95 BERG HEINRICH'S.
